UNITED STATES PATENT OFFICE

93,308

DESIGN FOR A SERVICE STATION BUILDING OR THE LIKE

Charles A. Urbanek, Chicago, Ill., assignor to Standard Oil Company, Chicago, Ill., a corporation of Indiana

Application May 23, 1934, Serial No. 51,898

Term of patent 14 years

To all whom it may concern:

Be it known that I, CHARLES A. URBANEK, a citizen of the United States, residing at Chicago, in the county of Cook and State of Illinois, have invented a new, original, and ornamental Design for a Service Station Building or the like, of which the following is a specification, reference being had to the accompanying drawings, forming part thereof, in which:

I claim:

The ornamental design for a service station building or the like, substantially as shown.

In witness whereof, I have affixed my signature.

CHARLES A. URBANEK.
